UNITED STATES PATENT OFFICE.

CHARLES ALOYSIUS McCARTY AND WALTER AUGUSTUS HOWLAND JONES, OF PLYMOUTH, MASSACHUSETTS; SAID JONES ASSIGNOR TO SAID McCARTY.

WATER-HEATING SYSTEM.

Application filed March 12, 1924. Serial No. 698,812.

To all whom it may concern:

Be it known that we, CHARLES A. McCARTY and WALTER A. H. JONES, citizens of the United States, and residents of Plymouth, in the county of Plymouth and State of Massachusetts, have invented a new and Improved Water-Heating System, of which the following is a full, clear, and exact description:

10 This invention relates to improvements in water heating systems, and has particular reference to such a system as used in connection with washing machines.

15 In large establishments, such as woolen mills, where batteries of washing machines are employed it has been found that the use of excessive amounts of fuel, such as coal, has been necessary in order to maintain the water used in the washing machines at 20 proper temperatures.

25 It is proposed by the present invention to effect an economy in fuel consumption by the provision of an apparatus by means of which the temperature of cold water is increased previous to its entry into the washing machines through the utilization of water discharged from said machines.

30 Another object is to provide an apparatus of simple and inexpensive construction and which is effective in carrying out the purpose for which it is designed.

35 The above and other objects will appear more clearly from the following detailed description, when taken in connection with the accompanying drawings, which illustrate a preferred embodiment of the inventive idea.

In the drawings—

40 Figure 1 is a diagrammatic view showing the application of the invention to a battery of washing machines, the tank being in section; and

Figure 2 is a plan view of said tank.

45 Referring more particularly to Figure 1, a pair of washing machines comprising a battery are indicated by the numeral 5 and these machines are supported in any suitable manner above the tank or vat 6 forming one of the essential features of the present invention. A water heater usually employed in connection with the washing machines 5 is also conventionally shown in Figure 1 and indicated by the numeral 7. This heater may be of any desired type, such as an instantaneous heater, and is utilized to increase

the temperature of the water previous to its 55 being fed into the washing machines through the main feed pipe 8 and the branch feed pipes 9, each of the latter pipes leading to one of said machines. The water to be supplied to the machines 5 may be taken 60 from any suitable source and is pumped to said machines by means of a suitable pump 10, also conventionally shown in Figure 1. Should it be desired to supply cold water directly to the machines 5 this may be done 65 through the pipe 11 which is connected by branches 12 to said machines, the flow of water through said pipe 11 being controlled by a gate valve 13 in said pipe. However, should it be desired to heat the water before 70 entering the machines the valve 13 is kept closed so that the cold water from the source of supply will not enter the pipe 11, but flow downwardly into the inlet pipe 14 which projects into the tank 6 to a point adjacent 75 the bottom thereof. Associated with the inlet pipe 14 is an outlet pipe 15 and connecting these two pipes are series of coils 16 each including a pair of pipes having adjacent ends connected to the pipes 14 and 80 15 and their opposite ends connected by a union 17, said coils combining to form a primary heating unit designed to increase the temperature of the water flowing from the source of supply before entering the 85 heater 7. The flow of water through the inlet pipe 14 is controlled by a gate valve 18 which is opened when it is desired to heat the water and which is kept closed when cold water is fed directly to the machines through 90 the pipe 11.

The tank 6, which is formed of concrete or any other desirable material, is provided at one end with spaced partitions 19 and 20, the former of which extends from the open top of the tank to a point adjacent the bottom thereof, while the latter partition which is interposed between the partition 19 and one end of the tank extends from the bottom to a point near the top, the height of 95 said partition 20 determining the water level in the tank when the same is supplied with the heated water discharge from the machines 5, as will be presently described. The water in the tank 6 which overflows the partition 20 is carried away through a suitable drain 21. Should it be desired to completely empty the tank a gate valve 22 is employed 100 105

to uncover the opening 23 in the partition 20 to permit the water to flow from the tank into the drain 21.

Each of the machines 5 is provided with 5 a drain outlet, conventionally indicated by the numeral 24 and connected to each drain outlet is a discharge pipe 25 extending in opposite directions from the drain outlet 24. One end of each pipe overhangs the 10 compartment formed by the partition 20 and the adjacent end of the tank while the opposite end of each pipe 25 is positioned over the tank adjacent the end thereof opposite the partition 20. A normally closed 15 gate valve 26 in each of the pipes 25 controls the flow of water from the machines 5 to the drain outlet 21 while similar valves 27 control said flow from the machines into the body of the tank. Should it be desired 20 to increase the temperature of the water pumped into the system by the pump 10 before it reaches the heating element 7 the used water in the machines 5, which has been previously heated to the proper tem- 25 perature, may be discharged from the machines 5 into the tank 6 by opening the valves 27. This water rises to the level of the top of the partition 20 and in so doing the coils 16 are immersed therein and heated 30 by said water so that as the water from the inlet pipe 14 passes through the coils its temperature is increased materially before it enters the inlet pipe 15 from whence it flows to the heater 7. Here the water is 35 raised to the desired temperature and then fed through the pipe 8 and branch pipes 9 to the machines 5. In the event that it is desired to discharge the water from the machines 5, as at the completion of the opera- 40 tion thereof, without permitting said water to flow into the tank 6 the valves 26 are opened thereby permitting the water from the machines to flow through the drain 21.

What is claimed is:

45 1. The combination with a washing ma-
chine and a heating element connected with
the machine for supplying heated water
thereto; of a tank above which said machine
is supported and into which the water in
50 the machine is directly discharged, a heat-
ing coil in said tank for raising the tem-
perature of water fed to said coil from a
source of supply, and a connection between
said coil and heating element for feeding
55 the water to the latter subsequent to its pas-
sage through said coil.

60 2. The combination with a washing ma-
chine and a heating element connected with
the machine for supplying heated water
thereto; of a tank above which said ma-
chine is supported, a heating coil in said
65 tank for raising the temperature of water

fed to said coil from a source of supply, a connection between said coil and heating element for feeding the water to the latter subsequent to its passage through said coil, and means for permitting the heated water from said machine to be discharged directly into said tank to heat the coil therein.

65 3. The combination with a washing ma-
chine and a heating element for supplying
heated water thereto; of a tank having a
drain outlet, a heating coil in said tank
for raising the temperature of water fed
70 to said coil from a source of supply, a con-
nection between said coil and heating ele-
ment for feeding water to the latter sub-
sequent to its passage through said coil, means
for permitting the flow of heated water from
75 said machine directly to said tank to heat
the coil therein, and means for discharging
water from said machine directly through
said drain outlet without affecting said coil.

80 4. The combination with a washing ma-
chine and a heating element for supplying
heated water thereto; of a tank having a
partition therein forming a compartment
in the tank and providing an overflow for
85 the tank below the level of the top thereof,
a drain outlet on one side of said partition,
water feeding means on the opposite side
thereof connected to a suitable source of
90 supply and also to said heating element,
means for discharging heated water from
said machine into said tank to immerse said
feeding means whereby the temperature of
95 the water passing therethrough is increased
prior to its entry into said heating element,
and means also permitting the discharge of
water from said machine into said tank and
100 through said drain outlet without affecting
said feeding means.

105 5. The combination with a washing ma-
chine and a heating element for supplying
heated water thereto; of a tank having a
partition therein providing an overflow for
the tank below the level of the top thereof,
a drain outlet on one side of said partition,
water feeding means on the opposite side
thereof connected to a suitable source of
110 supply and also to said heating element,
means for discharging heated water from
said machine into said tank to immerse said
feeding means whereby the temperature of
115 the water passing therethrough is increased
prior to its entry into said heating element,
means also permitting the discharge of
water from said machine into said tank and
120 through said drain outlet without affecting
said feeding means, and a valve associated
with said partition for permitting the tank
to be emptied through said drain outlet.
